F. L. WOOD

ROLLER SHADE FASTENING DEVICE

Filed Dec. 17, 1924

UNITED STATES PATENT OFFICE.

FRANK L. WOOD, OF LYNDEN, WASHINGTON.

ROLLER-SHADE-FASTENING DEVICE.

Application filed December 17, 1924. Serial No. 756,577.

To all whom it may concern:

Be it known that I, FRANK L. Wood, a citizen of the United States, residing at Lynden, in the county of Whatcom and 5 State of Washington, have invented a new and useful Roller-Shade-Fastening Device, of which the following is a specification.

My invention relates to improvements in roller shade fastening devices, and the object of my improvement is to provide simple and not expensive means for fastening shades on spring rollers, more especially when said rollers are made of wood, which can not be torn loose at the points of fastening by forces less than those which will destroy the shade.

I attain this object with the device illustrated in the accompanying sheet of drawings in which Figure 1 is a perspective view 20 of the upper end of a shade with my improvement in place, and Fig. 2 is a perspective view of a spring shade roller with my improved shade fastened in place thereon.

Similar characters refer to similar parts 25 throughout. Certain parts are broken away for lack of space.

More particularly: Near the upper end α^3 of shade 3 is fastened one end of fabric fastening strip 4 by attaching said strip end transversally across the shade at 5 by stitching, as indicated, or in any other desired and satisfactory manner, thus providing bifurcated ends α^3 and 4.

To fasten shade 3 on wooden, spring shade 35 roller 6 said roller is placed between the bifurcated upper ends of the shade and said ends are closely wrapped around the roller and overlapped at 7, and then said overlapped ends of shade 3 and fastening strip 40 4 are fastened to each other and to roller 6 by tacks, the heads of which are shown at 8.

When the shade is thus fastened to the roller it can never be unwound farther than 5 from which line the strain on the shade is

divided between the ends α^3 and 4, and a force sufficient to tear loose the illustrated fastening would be more than enough to tear the shade apart transversally.

When fastened as described the mounted shade operates as usual. That is, the short 50 shaft 9 is held from turning in the shade bracket by its flattened end while pawls 10, which are pivoted on the end of the roller 6 allow the roller to revolve in one direction on the shaft but prevent its revolution in 55 the other direction while they are engaged, and the spring within the roller, not shown, which reacts between said shaft and roller, acts to revolve said roller against said pawl control, as is well known.

Having thus disclosed my invention, what I claim as new and desire to secure by Letters Patent is,—

1. In combination, a roller shade the inner 65 end of which is adapted for fastening to one side of a shade roller, and a strip of fabric one edge of which is fastened to said inner end of said shade transversally therewith and proximate thereto adapted for fastening to the other side of said shade roller and together with said inner shade end embrace 70 said shade roller and the junction of said strip and said shade adapted to roll up on said shade roller without folding either said shade or said strip.

2. In combination, a shade roller, a roller shade the inner end of which is fastened to one side of said roller, and a strip of fabric the inner edge of which is fastened transversally to the said inner end of said shade 80 with said inner edge thereof proximate to said inner shade end the other edge of which is fastened to the other side of said roller and together with said inner shade end embrace 85 said roller and the junction of said shade and said strip adapted to be rolled up on said roller without folding.

FRANK L. WOOD.
